UNITED STATES PATENT OFFICE.

THOMAS B. JEFFERY, OF RAVENSWOOD, ILLINOIS.

VELOCIPED.

SPECIFICATION forming part of Letters Patent No. 411,035, dated September 17, 1889.

Application filed October 15, 1888. Serial No. 288,096. (No model.)

To all whom it may concern:

Be it known that I, THOMAS B. JEFFERY, a citizen of the United States, residing at Ravenswood, county of Cook, and State of Illinois, have invented certain new and useful Improvements in Velocipedes, which are fully set forth in the following specification, reference being had to the accompanying drawings, forming a part thereof.

10 In the drawings, Figure 1 is a detail sectional side elevation showing the frame-work of my improved velocipede, section being made in the vertical plane of the steering-head axis at the upper and lower bearings of the steering-head and at the junction of the two arms of the frame. Fig. 2 is a side elevation, and Fig. 3 an axial section, of the upper steering-head bearing of a slightly modified form from that shown in Fig. 1. Fig. 4 is a 15 detail of the seat-supporting spring and bracket on a larger scale than Fig. 1. Figs. 5 and 6 are detail perspectives of alternative forms of junction of two branches of the seat-supporting frame. Fig. 7 is a section at the line 7 7 on Fig. 1. Fig. 8 is a perspective detail of the sleeve which constitutes the adjustable bearing of the steering-head.

A is the rear driving-wheel frame or fork. B represents the outline of the rear driving-wheel.

C is the pedal-crank shaft.

D is a two-part box secured to the seat-supporting frame and constituting the means of pivoting said frame to the rear driving-wheel frame or fork. The seat-supporting frame and steering-head are formed as a single rigid frame, comprising the parts D', D², and D³, the last being the steering-head proper, all of said parts being tubular. The part D' extends from the pivot above the pedal-crank shaft upwardly and with a slightly rearward inclination, and at its upper end has the seat-support inserted in it. At the lower part the boss D' curves forward, so that it terminates at the lower end approximately horizontally, and to said lower end there is secured the arm D², which extends almost straight upwardly and forwardly to its junction with the lower part of the steering-head B³. Both the junctions of the part D² with the adjacent parts D and D³ may be made in either of the

ways shown in Figs. 5 and 6—that is, either of the two joined parts may terminate in diverging lugs d, which clasp and are brazed to the other part, the end of the part having the 55 lugs abutting against the side of the clasped part. The advantage of this construction is that a shorter turn can be made than would be possible by bending the tubular arms without danger of weakening or cracking them, 60 and that a neater and lighter junction is effected than could be made by a separate junction-piece secured to each, and that neither part is weakened, as would be the effect of screw or rivet holes.

E is the steering-wheel fork. To its upper end there is secured the cup-shaped fitting E', which forms one part of the steering-head lower bearing, and a similar fitting E¹⁰, adapted to have its end inserted within the 70 steering-head, is secured to the upper end of the steering-head. To the lower end of the steering-head there is secured the fitting E², which has the flange e² fitting outside of the upper edge of the fitting E', while the boss or 75 main body portion of said fitting E² enters within the cup of the fitting E', whereby the two parts E' and E² are accurately retained in relation to each other. The lower face or end of the part E² has an annular groove to 80 receive the anti-friction balls E³, which bear in said groove and on the concave upper surface of the cup-shaped fitting E'. The fitting E² has an upwardly-projecting annular flange e²⁰, which fits within the lower end of the 85 steering-head, and by means of which said steering-head and fitting are rigidly secured together.

E⁴ is the steering rod or spindle, which is rigidly secured to the upper end of the fork 90 E and to the fitting E', and which passes through the central opening in the fitting E², and thence up to the steering-head, and through the fitting E¹⁰, above which it protrudes as the upper end of the steering-head. 95 To said spindle there is made fast, in the manner hereinafter described, the sleeve E E²⁰, which corresponds to the fitting E² at the lower end of the steering-head, having on its under face an annular groove for anti-friction 100 balls E³⁰, which bear also upon the upper concave face of the fitting E¹⁰. The sleeve E²⁰ is

secured to the spindle E⁴ by means of the clamp E⁵ which encircles it, and terminates in lugs e⁵, through which the clamping-bolt E⁵⁰ is passed to draw them together and pinch 5 or contract the sleeve E²⁰ within said clamp, to cause it to bind firmly upon the spindle E⁴.

In order to retain the clamp E⁵ about the sleeve E²⁰, the latter is preferably provided with the flange e³⁰ at the upper end. By this 10 construction the steering-head is retained between the two ball-bearing joints described, the one at the upper and the other at the lower end of the steering-head, and in order that these bearings may be kept at all times 15 from play longitudinally with respect to the steering rod or spindle, the sleeve E²⁰ may be from time to time adjusted on the spindle by loosening the clamp E⁵ and tightening it again after the sleeve is adjusted to the desired position.

It may be found desirable in some cases to employ a tubular steering-rod, which will of necessity be of greater diameter than the solid spindle or rod E⁴. Such construction is 20 illustrated in Figs. 2 and 3, and when it is adopted the sleeve E²⁰ may have its upper edge made in a spiral form, as illustrated in Fig. 2, thereby constituting a cam which may operate against a stud e⁴, projecting from the 25 rod E⁴, its position when the parts are originally assembled being at the lowest point of the spiral cam of the sleeve E²⁰ when the ball-bearings are adjusted properly and without 30 undue play. When this construction is adopted, the clamp E⁵ will be fastened to the 35 sleeve E²⁰, preferably at a point opposite the lugs E⁵, as by means of the screw e⁵⁰, and when it is desired to adjust the ball-bearings to take up any lost motion, the clamping-bolt 40 E⁵⁰ being loosened, the clamp carrying with it the sleeve E²⁰ will be pushed round on the rod E⁴, the spiral cam edge operating against the stud e⁴, with a tendency to crowd the 45 sleeve E²⁰ downward on the steering-rod until all lost motion is taken up.

In order to permit the sleeve E²⁰ to be contracted, as described, by the clamp E⁵ sufficiently to bind upon the steering-rod E⁴, it is necessary either to make the sleeve quite thin 50 at the part where it is encircled by the clamp, so that it will readily yield to the pressure of the latter, or to split it, as illustrated in Fig. 8.

The adjustment herein provided for opposite ball-bearings is not limited in its application to the steering-head, but may be made use of in many similar situations, the steering-rod being in effect an axle, and I do not limit myself to the use of this device on a 55 steering-head alone.

The seat is designed to be secured upon the horizontal arm H¹ of the angular bracket H, the vertical arm being adjustably secured in the bracket H². The last-mentioned bracket 60 is supported upon the two ends K' K² of the similar springs K K. Said springs are both secured to the expanded portion G' of the

rod G, which is inserted in the upper end of the frame-arm D, and secured adjustably at any desired height in said arm by the clamp G', which encircles the end of the arm D and serves to contract the same about the rod G. The springs K K consist each of two spiral coils k' and k² and the straight portion k³, extending from coil to coil, and the ends K' K², 70 running from the coils k' k², respectively. Said ends K' and K² are parallel to each other, and parallel also to the corresponding ends of the other spring. The ends K' of the two springs are connected by a shaft K⁴, and the ends K² by a similar shaft K⁵, and upon said shafts K⁴ and K⁵ the bracket H is hung. The straight portion k³ between the coils affords the means of securing the springs to the flat portion G' of the rod G, as stated, and 80 this may be done in any convenient manner, as by the bolts K⁴ and K⁵, as illustrated. The ends K' and K² act as parallel links to guide the seat and keep the vertical arm of the bracket H in all positions substantially parallel to the rod G. The four ends of the two springs each project from one of the coils with a downward inclination, whereby the movement of the seat when jarred by the wheel encountering an obstruction is backward and 85 downward, as is desirable. A spring L is provided, located, preferably, near the pivot of the driving-wheel fork to the seat-supporting frame, and reacting between said two parts to uphold the latter yieldingly. The 90 form and action of this spring are familiar, and need not be further described. The 95 brake M is sustained by a spring-arm M', which is secured to the steering-wheel fork on both sides of the vertical plane of the 100 steering-wheel, both ends of the arm being thus made fast, the brake being attached to the intermediate portion, which normally holds it off the wheel and yields to allow it to contact the wheel, the spring-arm being the 105 110 only support or connection necessary.

I claim—

1. In a velocipede, a rigid frame intermediate the driving-wheel fork and the steering-wheel fork, and made of tubular parts successively joined together, each joint being made by diverging lugs on the end of one of the joined parts clasping the other part, said end abutting against the side of the clasped part, substantially as set forth.

2. In a velocipede, in combination with the rear driving-wheel fork or frame, a frame pivoted thereto and comprising the steering-head and a seat-supporting arm, said steering-head and said arm being connected together by a cross-arm joined to the lower end of each, each of said junctions being made by diverging lugs on the end of one of the joined parts clasping the other part, said end abutting against the side of the clasped part, substantially as set forth.

3. In a velocipede, in combination with the fork, the upwardly-concave fitting E', terminating the fork at the upper end, the steer-

ing-head terminating at the lower end in a fitting E², having the flange e², adapted to fit outside the upper edge of the fitting E', and having a central boss adapted to enter the 5 concavity of E', said boss having a ball-bearing groove on its under face, and the balls located in the concavity of the fitting E' and in said groove, and the steering-rod rigid with the fork and extending through the 10 head, and a suitable stop-bearing for the upper end of the head, secured to the rod above the latter, substantially as and for the purpose set forth.

4. In combination with an axle and the 15 part which revolves thereon, a sleeve on the axle constituting the bearing at one end for the revolving part and longitudinally extended beyond the portion which constitutes such bearing, and a clamp embracing such 20 longitudinal extension, whereby the latter may be contracted about the axle to bind the sleeve thereon, substantially as set forth.

5. In combination with an axle and the part which revolves thereon, a sleeve located on 25 the axle and serving as the bearing of the revolving part and longitudinally extended beyond the part which constitutes such bearing, and having the end or edge of such longitudinally-extended part oblique, and a stud 30 projecting from the axle in contact with such oblique end, whereby the rotation of the sleeve on the axle tends to adjust it longitudinally thereon, substantially as set forth.

6. In combination with an axle, a sleeve 35 thereon which has the bearing for the part

which revolves upon the axle, said axle having a stop which abuts against the end of the sleeve, one of said abutting parts having an oblique edge, whereby the rotation of the sleeve causes it to be adjusted longitudinally 40 thereon, substantially as set forth.

7. In combination with an axle, a sleeve located thereon, constituting an adjustable bearing and extended longitudinally on the axle beyond the part which serves as a bearing, a clamp encircling such extended part, whereby it may be contracted to bind the sleeve onto the axle, a stop fixed on the axle and abutting against the end of the sleeve, one of said abutting parts having an oblique 45 edge, whereby the rotation of the sleeve causes it to be adjusted longitudinally, a clamp being secured at one point to the box, whereby it serves both to adjust and to secure the sleeve in adjusted position, substantially as 50 set forth.

8. In a velocipede, in combination with the wheel, a spring-arm rigidly secured to the fork on both sides of the vertical plane of the wheel, and the brake-shoe attached to the 55 spring-arm intermediate the points at which it is thus secured and overhanging the wheel, substantially as set forth.

In testimony whereof I have hereunto set my hand, in the presence of two witnesses, at 60 Chicago, this 12th day of October, A. D. 1888.

THOS. B. JEFFERY.
